ROBERT M. KEENEY AND PHILIP JAY LONERGAN, JR., OF DENVER, COLORADO; SAID LONERGAN ASSIGNOR TO SAID KEENEY.

ELECTRODE HOLDER.

1,406,741.

Specification of Letters Patent. Patented Feb. 14, 1922.

Application filed January 20, 1920. Serial No. 352,816.

To all whom it may concern:

Be it known that we, ROBERT M. KEENEY and PHILIP JAY LONERGAN, Jr., citizens of the United States, residing at Denver, in the county of Denver and State of Colorado, have invented certain new and useful Improvements in Electrode Holders, of which the following is a specification.

This invention relates to electrode holders of the type used in electric smelting furnaces for the transmission of electricity to and through the charge thereof.

Holders of this character, which are specifically designed to support the heavy carbon or graphite electrodes used in electric smelting furnaces, in the proper position for the passage of electricity between them, and at the same time transmit the electric current from the source of supply to the electrodes, are constantly subjected to the intense heat generated in the smelting chamber of the furnace and to the corrosive influence of the gases of combustion.

In the form of electrode holders of this type at present most commonly used, the cooperating members thereof are composed of parts which are bolted together.

It frequently occurs that these parts when subjected to the influence of the heat expand unevenly and separate, thereby permitting the corrosive gases to form an oxidizing film between them, which increases the resistance to the flow of electricity and compels the bolts by which the parts are connected to carry the greater part of the electric current.

The consequent overload tends to break the connections between the parts, thereby incapacitating the holder with the result that the operation of the furnace must be discontinued until it is either repaired or replaced.

The holders at present in use are furthermore defective in that their replacement or repair in case of breakage, are attended by mechanical and electrical difficulties which render the operation costly in time as well as money and in that they are incapable of efficiently performing their functions for any length of time under the influence of excessive heat and corrosive gases.

In view of the above, it is the primary object of the present invention to provide

an electrode holder for electric furnaces in which an integral and heat-resisting construction eliminates to a great extent the difficulties heretofore experienced and in which the provision of interchangeable members of very simple construction permits of their being replaced or repaired in case of breakage at a very nominal cost.

Other objects of our invention reside in providing strong and readily adjusted means for the connection of the members of which the holders are composed and in allowing a limited self-adjusting movement of the connected parts to compensate for irregularities in the form of the electrodes with which the parts engage.

The above and other objects, all of which will be fully described in the course of the following description, we attain by the construction and arrangement of parts shown in the accompanying drawings, in which

Figure 1 is a partly broken plan view of our improved electrode holder;

Figure 2, a side elevation of the same;

Figure 3, an end view of the holder looking in the direction of the arrow A, Figure 1.

Figure 4, a section on the line 4—4, Figure 1 looking in the direction of the arrow drawn across said line, and

Figure 5, a fragmentary plan view of one of the arms of the holder showing a modification in their construction.

Referring to the drawings, our improved electrode holder is composed of two members 5 which are identical in form and construction and which are hinged together through the medium of an interposed link 6. Each member is composed of a curved jaw 7 integrally formed at the end of a bus-arm 8 of sufficient length to extend outside the smelting chamber of the furnace on which the electrodes are employed.

The jaw is reenforced by external ribs 9 and longitudinally bored transverse bosses 10 and it has at its outer end a lip 12 for the application of connecting means herein-after to be described.

A pair of spaced ears 13 extending inwardly from the opposite end of the jaw cooperate with the before-mentioned link to hingedly connect the members, and cavities 14 within the body portions of the jaws

provide water chambers for cooling purposes.

Hanger-bolts 15 extending through the hollow bosses and fastened by nuts 16 at the under side thereof provide means for the suspension of the holder in the furnace, and lugs 17 formed at the outside of the arms of the members are used for the same purpose. The bus-arms of the members 10 are bent at right angles at their outer ends for their connection with the flexible conductors of electricity, and they are bored to support pipes 18 which connect with the internal chambers of their respective jaws 15 to conduct water thereto from a convenient source of supply.

The link 6 which connects the members at the inner ends of their curved jaws is curved to cooperate therewith in gripping an electrode placed between them.

The link which is inserted at its ends in the spaces between the ears 13 of the two members of the holder is pivotally secured by pins 19 extending through aligned apertures in the ears and its respective ends, the apertures of the link being somewhat larger than the diameter of the pins to permit of a limited self-adjusting movement of the link to compensate for irregularities in the form 30 of the electrodes.

Cotters 20 in apertures in the upper ends of the pivot pins prevent their downward displacement.

The means for fastening the jaws together 35 at their outer ends consist in the preferred form of our invention of a key 21 which extends through slots in the outwardly projecting lips of the members of the holder, in which it is snugly fitted, and which is slotted 40 for the reception of wedges 22 which by engagement with the outer surfaces of the lips securely lock the parts together.

Pins 23 in apertures of the wedges prevent their displacement.

45 The members of the holder are made of cast metal or an alloy of metals and are of the proper size and proportions to securely support the heavy electrodes and to withstand heat and external stress without detrimental deformation and their bus arms are made of sufficient length to extend beyond the path of the flames and gases in the furnace.

The interchangeability of the members 55 and the simple means provided for their connection facilitate repairs and replacement and greatly reduce the expenses connected therewith and the one-piece construction of the conducting members effectively 60 prevents short circuiting or overloading of any one part thereof.

In the construction shown in Figure 5, the bus-arms of the holders are composed of spaced and integrally interconnected longi-

tudinal plates or laminæ 24 which decrease 65 the cost of material and increase the carrying capacity of the arms for electric current.

It will be understood without further illustration that when the arms are thus constructed 70 the pipes for conveying water to the chambers of the jaws must be placed exteriorly thereof.

Having thus described our invention what we claim and desire to secure by Letters- 75 Patent is:

1. An electrode holder of the character described comprising a pair of cooperating clamping members each composed of a jaw and a bus-bar formed together of one piece 80 of metal.

2. An electrode holder of the character described, comprising a pair of cooperating clamping members each composed of a jaw having apertured reinforcing bosses, a bus-bar made integral with the jaw, and hanger-bolts in the apertures of the bosses.

3. An electrode-holder of the character described comprising a pair of clamping members each composed of a jaw, a bus-bar made integral therewith and a pair of apertured ears at the juncture of the bus-bar and the jaw, and a link pivoted between the ears of the members.

4. An electrode holder of the character described comprising a pair of clamping-members each composed of a curved faced jaw and a bus-bar made integral therewith, and a curved link pivotally connecting the members in continuity with the curved faces 100 of their jaws.

5. An electrode-holder of the character described comprising a pair of clamping-members each composed of a curved faced jaw and a bus-bar made integral therewith, 105 and a curved link pivotally connecting the members, said link having an independent self-adjusting movement with relation to the jaws.

6. In an electrode holder of the character described, a clamping member having a jaw and a bus bar made integral therewith and composed of a plurality of spaced, integrally connected laminæ.

7. In an electrode holder of the character described, a clamping member having a jaw and a bus bar made integral therewith and composed of a plurality of spaced laminæ.

8. In an electrode holder, a pair of clamping members each comprising a jaw and a 120 bus bar in rigid connection therewith, a link connecting the members at the junctures of their jaws and bus bars, and means at the free ends of the jaws for fastening them together.

9. In an electrode holder, a pair of clamping members each comprising a jaw and a bus bar in rigid connection therewith and

pivottally connected at the junctures of their jaws and bus bars, and means for fastening the free ends of the jaws together.

10. In an electrode holder, a pair of clamping members each comprising a curved jaw having a projecting lip at one end, and a bus bar rigidly connected with the jaw at its other end, means applied to the lips for

fastening the jaws together, and a link connecting the members at the junctures of 16 their jaws and bus bars.

In testimony whereof we have affixed our signatures.

ROBERT M. KEENEY.

PHILIP JAY LONERGAN, JR.
